Patented Apr. 9, 1963

194,969

CANOPIED SERVICE BOOTH OR SIMILAR ARTICLE

Joseph Stanley McGee, Dorval, Quebec, George Jacques Miron, Montreal, Quebec, and Margaret E. A. Pitt, Westmount, Quebec, Canada, assignors to Modenco Ltd., Montreal, Quebec, Canada

Filed Aug. 25, 1960, Ser. No. 61,889

Term of patent 14 years

(Cl. D13—1)

Fig. 1

Fig. 2

Fig. 3

FIGURE 1 is a front perspective view of a canopied service booth showing our new design;

FIGURE 2 shows the said design in top plan;

FIGURE 3 shows the said design in side elevation, the right-hand side being shown;

FIGURE 4 is a rear elevational view thereof; and

FIGURE 5 is a transverse cross-sectional view thereof taken on line 5—5 of FIGURE 4.

We claim:

The ornamental design for a canopied service booth or similar article, as shown.
